UNITED STATES PATENT OFFICE.

THOMAS TAYLOR, OF HANLEY, ENGLAND.

DESIGN FOR AN EGG-BOILER.

49,405.

Specification for Design.

Patented July 18, 1916.

Application filed May 22, 1916. Serial No. 99,243. Term of patent 7 years.

To all whom it may concern:

Be it known that I, THOMAS TAYLOR, subject of the King of Great Britain, residing at Eastwood, Hanley, county of Stafford, England, have invented a new, original, and ornamental Design for an Egg-Boiler, of which the following is a specification.

The drawing represents an elevational view of an egg boiler, showing the new design.

What I claim as new and desire to secure by Letters Patent, is:—

Copies of this patent may be obtained for five cents each, by addressing the "Commissioner of Patents, Washington, D. C."

The ornamental design for an egg boiler, as shown.

In testimony whereof I have hereunto set my hand in presence of two subscribing witnesses.

THOMAS TAYLOR.
